CLAIM

The ornamental design for a sheet retainer, as shown and described.

DESCRIPTION

FIG. 1 is an isometric view of a first embodiment of a sheet retainer of the present invention;

FIG. 2 is a top plan view of the sheet retainer of FIG. 1, (the bottom plan view being a mirror image of the top plan view);
FIG. 3 is a side view elevation of the sheet retainer of FIG. 1, as taken from the left side;FIG. 4 is an end view of the sheet retainer of FIG. 1, as taken from the right end (the left end view being a mirror image);
FIG. 5 is a side view elevation of the sheet retainer of FIG. 1, as taken from the right side;

FIG. 6 is an isometric view of a second embodiment of a sheet retainer of the present invention;

FIG. 7 is a top plan view of the sheet retainer of FIG. 6 (the bottom plan view being a mirror image of the top plan view);
FIG. 8 is a side view elevation of the sheet retainer of FIG. 6, as taken from the right side;

FIG. 9 is an end view of the sheet retainer of FIG. 6, as taken from the right end (the left end view being a mirror image); and,

FIG. 10 is a side view elevation of the sheet retainer of FIG. 6, as taken from the left side.
